UNITED STATES PATENT OFFICE.

ANTHONY BIZZARRI, OF NEW YORK, N. Y.

DESIGN FOR A BABY CARRIAGE OR SIMILAR ARTICLE.

Application filed April 23, 1927. Serial No. 21,707. Term of patent $3\frac{1}{2}$ years.

To all whom it may concern:

Be it known that I, ANTHONY BIZZARRI, a subject of the King of Italy, residing at New York, in the county of New York and State of New York, have invented a new, original, and ornamental Design for a Baby Carriage or Similar Article, of which the following is a specification, reference being had to the accompanying drawing, forming part thereof.

Referring to the drawing:

Fig. 1 is a front elevation;
Fig. 2 is a view in perspective;
Fig. 3 is a side elevation; and
Fig. 4 is a plan view of a baby carriage or similar article showing my new design.

I claim:

The ornamental design for a baby carriage or similar article as shown.

ANTHONY BIZZARRI.
